SURGICAL CAP

Valerie G. Rudolph, 179 Mount Airy, St. Paul, Minn.

Filed Sept. 18, 1959, Ser. No. 57,604

Term of patent 14 years

(Cl. D3—13)

FIG. 1.

FIG. 2.

FIG. 3.

FIG. 4.

FIGURE 1 is a right side elevational view of a surgical cap embodying my new design as it appears when tied in position for use;

FIGURE 2 is a front elevational view thereof in the untied position;

FIGURE 3 is a slightly enlarged left side elevational view thereof; and

FIGURE 4 is an enlarged fragmentary cross-sectional view thereof taken on line 4—4 of FIGURE 3.

It is understood that the lines representing fabric extend throughout the surface of the entire areas in FIGURES 1, 2, and 3.

I claim:

The ornamental design for a surgical cap, as shown and described.
